[57] CLAIM

The ornamental design for a mobile telephone, as shown and
described.

DESCRIPTION

FIG. 1 is a left, front perspective view of a mobile telephone, in a closed position and without a battery attached, showing my new design;

FIG. 2 is a right, front perspective view thereof, in an open position;

FIG. 3 is a front elevational view thereof;

FIG. 4 is a right side elevational view thereof;

FIG. 5 is a bottom view thereof;

FIG. 6 is a rear elevational thereof;

FIG. 7 is a left side elevational view thereof;

FIG. 8 is a top view thereof;

FIG. 9 is a left, front perspective view of a further embodiment of a mobile telephone, in a closed position and with a battery attached, showing my new design;

FIG. 10 is a right, front perspective view thereof in an open position;

FIG. 11 is a front elevational view thereof;

FIG. 12 is a right side elevational view thereof;

FIG. 13 is a bottom view thereof;

FIG. 14 is a rear elevational view thereof;

FIG. 15 is a left side elevational view thereof;

FIG. 16 is a top view thereof;

FIG. 17 is a right, rear perspective view thereof, in a closed position;

FIG. 18 is a right, rear perspective view thereof, in an open position;

FIG. 19 is a right, front perspective view of a further embodiment of a mobile telephone, in an open position and with a battery attached, showing my new design;

FIG. 20 is a front elevational view thereof;

FIG. 21 is a right side elevational view thereof;

FIG. 22 is a bottom view thereof;

FIG. 23 is a rear elevational view thereof;

FIG. 24 is a left side elevational view thereof;

FIG. 25 is a top view thereof;

FIG. 26 is a left, rear perspective view thereof; and,

FIG. 27 is a left, rear perspective view thereof, in a closed position.
